BYERS W. KADEL, OF BALTIMORE, MARYLAND.

CAR TRUCK.

Application filed April 1, 1926. Serial No. 99,063.

This invention relates to trucks for railway cars and, more particularly, to the construction of the side frames and associated spring plank, bolster and spring plates, whereby an additional spring unit may be employed therewith for increasing the capacity of said trucks.

The principal object of my invention, generally considered, is the improvement in design of the side frames, bolster, spring plank and spring plates, whereby a greater number of springs than normally employed may be used without radically changing the construction of the associated parts.

15 An object of my invention is the employment of an A. R. A. standard five group nest of springs together with an additional spring group or unit spaced inwardly of the center spring of the standard nest of springs, whereby increased capacity of the truck is secured, the side frames, bolster, spring plank and spring plates being modified to a minimum extent for efficiently accomplishing the desired result.

20 Another object of my invention is the design of side frames, bolster, spring plank and associated spring plates for permitting the employment of an additional spring unit with each side frame associated with an A. R. A. standard five unit nest of springs, whereby increased truck capacity is secured, the spring plank seat portions of the side frames being so constructed and reinforced by webs or brackets, ribs and stools or 25 columns, whereby an adequate area sufficiently reinforced is provided for supporting the spring plank and its associated springs, spring plates and bolster.

25 A further object of my invention is the utilization of an additional spring unit of corresponding size with an A. R. A. standard five unit nest of springs positioned on spring plates and an associated spring plank, bolster and side frames so that the entire group of springs balances about the longitudinal center line of the side frame, the standard nest of springs, for that purpose, being positioned outwardly and the associated spring plank being correspondingly lengthened but formed of standard construction at its ends, the bolster being of standard construction except having the portion thereof engaging the supporting spring assembly locally extended to receive the addi-

tional spring unit which is inwardly positioned with respect to the center spring unit of the standard nest of springs.

30 A still further object of my invention is the provision of an additional spring unit associated with an A. R. A. standard five group nest of springs for increasing the capacity of car trucks with which employed, said additional spring unit being positioned inwardly of the center spring unit of the standard nest of springs and on substantially the transverse center line thereof, the associated spring plates being correspondingly extended to receive the extra spring unit and provided with locating bosses arranged on the longitudinal center line of 35 gravity for the complete six unit nest of springs, whereby said bosses are adapted for reception in positioning apertures of standard location in the associated spring plank, said spring plank being of standard construction at the ends thereof but correspondingly lengthened because of the necessary shifting of the standard group of springs so that the center of gravity of the complete group will correspond with the longitudinal 40 center line of the associated side frame, said spring plank and side frame being formed with apertures for receiving the spring retaining belt, said apertures being elongated transversely of the frame whereby they are 45 adapted for use with either the six unit nest of springs arranged in accordance with my invention or the A. R. A. standard nest of springs.

50 An additional object of my invention is the modification of the side frames, bolster and spring plank of a truck, whereby the same are adapted for use with either the A. R. A. standard five group nest of springs and associated spring plates or with such a 55 nest of springs and an additional inwardly spaced spring group with associated spring plates.

55 Other objects and advantages of the invention relating to the particular arrangement and construction of the various parts will become apparent as the description proceeds.

60 Referring to the drawings illustrating my invention, the scope whereof is defined by 105 the appended claims:

65 Figure 1 is a fragmentary side elevation of a truck, shown partly in section on the

line 1-1 of Figure 3 and particularly showing the construction of the various members associated with the springs positioned between the tension member of the side frame 5 and the truck bolster.

Figure 2 is a horizontal sectional view of a fragmentary portion of the truck on the line 2-2 of Figure 1 looking in the direction of the arrows.

Figure 3 is a transverse sectional view on the lines 3-3 of Figures 1 and 4 looking in the direction of the arrows.

Figure 4 is a plan of the spring plank seat portion of the truck side frame, the position of the springs thereover being indicated diagrammatically by dot and dash lines.

Figure 5 is a top plan of the bottom spring plate and is likewise a bottom plan of the top spring plate.

Referring to the drawings in detail, like parts being designated by like reference characters, a truck side frame 1 is shown fragmentarily and said frame, in the present embodiment, is of integral cast construction embodying a compression member 2, a tension member 3, and bolster guide columns or struts 4 spacing intermediate portions of said compression and tension members, leaving a bolster or window opening 5 therebetween. The compression member 2, over the bolster opening, is shown substantially channel or inverted U shape in cross section, the bolster guide columns are shown of similar construction at the bolster guiding portions thereof whereas the tension member 3, beneath the bolster opening 5, is illustrated as of box shape in cross section and formed with an upper web 6, a lower web 7, a front or outer web 8 and a rear or inner web 9, said webs 8 and 9 being upright or substantially vertical and extending between the webs 6 and 7. As will be apparent from a consideration of Figure 3, the webs 8 and 9 join the web 7 at the side edges thereof but the upper web 6, in order to form a spring plank seat portion of ample width, is extended laterally beyond the upper ends of the webs 8 and 9 forming outward or front flange or shelf portions 10 and inward or rear shelf or flange portions 11.

In the embodiment illustrated, the spring plank 12 rests directly on the upper web 6 of the tension member which forms the seating portion therefor and the upper surface of said spring plank seat portion is preferably formed with A. R. A. standard squaring lugs 13 which engage in corresponding apertures 14 in the spring plank for maintaining the desired relation between the spring plank 12 and side frame. The end of the spring plank 12 is of standard construction and provided with a regular A. R. A. embossment 15 to prevent the associated spring group from working out. In accordance with my invention, however, the length

of the spring plank is slightly greater than the standard spring plank because of the additional spring group or unit which may be used therewith although it is adapted for use with the A. R. A. standard five group nest of springs, if desired. The spring plank 12, as shown most clearly in Figures 1 and 2, is of channel construction and the web thereof is formed with spring plate locating apertures 16 so positioned that when the spring plank is assembled with the side frame, said apertures 16 are located on the longitudinal center line thereof.

Positioned on the web of the spring plank 12 is a spring plate 17 formed with locating bosses 18 which engage in the apertures 16 in the spring plank and properly position the spring plate 17 and the associated springs 19. In the embodiment illustrated, the bosses 18 are formed by pressing substantially conical extensions downwardly from the spring plate 17 but it is obvious that they may be of any desired construction. In accordance with my invention, I preferably employ an A. R. A. standard five group nest of springs which is positioned directly on the spring plate 17 and properly located with respect thereto by means of upstanding annular flanges or collars 20 which engage the innermost springs 21 of the spring groups or units 19.

Positioned inwardly of the center spring unit 19 of the standard nest of springs, in the present embodiment, is an additional spring unit or group of springs 22 preferably corresponding in size with the other spring groups or units of the standard nest of springs. In order to accommodate this extra spring unit or group, the spring plate 17 is correspondingly extended, as shown most clearly in Figure 5, and formed with an additional spring locating collar 23. The additional group of springs 22 is preferably spaced with respect to the springs of the standard group in accordance with the spacing between the springs of said group, preferably lies on the transverse center line of the central group of springs and is inwardly disposed with respect thereto. The locating bosses 18 are so arranged with respect to the collars 20 and 23 that the springs balance about said bosses, that is, said bosses preferably lie on the longitudinal center line of gravity of said springs so that, when engaged in the locating apertures 16 in the spring plank 12, the springs balance about the longitudinal center line of the frame, either when said springs are in accordance with my invention, as shown in the drawings, or if they are replaced by a standard five group nest of springs in which the locating bosses are also on the longitudinal center line of gravity of said springs.

The upper spring plate 24 may be constructed identical with the lower spring

plate 17 but is reversed in position so that the collars 20 and 23 extend downwardly and engage the inner springs 21 and the locating bosses 18 extend upwardly and engage in corresponding apertures, not shown, in the truck bolster 25. Referring particularly to Figure 3, it will be seen that because of the sixth spring group or unit 22, it is necessary to extend the substantially horizontal spring engaging web or face 26 of the bolster inward as shown at 27. This, however, is only done locally so as not to decrease the bolster strength at this point any more than is necessary, the outer sides of the sloping portion 28 of the lower web of the bolster starting to slope at its standard location, as indicated at 29, and the horizontally extended portion 27 of the web 26 being thickened, as indicated, to avoid decreasing the bolster strength.

For retaining the spring plates 17 and 24 in the desired assembled relation with respect to the springs therebetween, the spring locating collars engaging the central spring set or group of the standard nest of springs are preferably formed substantially semi-spherical in shape and, as indicated most clearly in Figure 3, provided with apertures 30 therethrough for the reception of a retaining bolt or other means 31 extending therebetween.

In order to allow for compression of the springs due to the load of the car, the spring plank 12 is apertured at 32 directly beneath the bolt 31 and the upper web 6 of the tension member of the side frame is correspondingly apertured at 33. In order that the apertures 32 and 33 may be adapted for use either with the spring arrangement shown in accordance with my invention or with the standard five unit nest of springs heretofore referred to, they are preferably elongated transversely as shown most clearly in Figures 3 and 4 so as to overlap the center line of the side frame 1 and allow for the reception of a bolt 31 positioned as shown in Figure 3 or for one positioned on the center line of the side frame in accordance with standard construction.

For adequately reinforcing the spring plank seat or upper web 6 of the tension member 3 of the side frame with respect to the novel arrangement of springs in accordance with my invention, said web 6 is preferably formed and reinforced as most clearly shown in Figures 3 and 4. From a consideration of these figures, it will be apparent that the front edge of the web 6 is extended in width to a maximum below the two outer spring groups or units 19 and between these points extends in a straight line at a uniform distance from the center line of the frame, as indicated at 34. Approximately directly beneath said outer springs, the extended flange 10 is preferably reinforced and braced

with respect to the web 8 by means of substantially triangular web or bracket portions 35. The inner edge of the web 6 or the free edge of the flange portion 11 thereof is increased in width to a maximum directly beneath the innermost or extra spring unit 22 as indicated at 36 and is there preferably reinforced by a substantially triangular web or bracket 37 extending from the web 9 of the tension member.

As a further reinforcement for the spring plank seat portion or web 6 of the tension member, a plurality of columns or stools 38 preferably angular or star shaped in cross section are provided between webs 6 and 7 of the tension member, said stools 38 serving principally for supporting the spring units above, and which, as shown most clearly in Figure 4, are those springs which lie directly inward of the two outermost spring units. Further spring plank seat reinforcing means, in accordance with the present embodiment, comprise the upright webs or ribs 39 and 40 which extend preferably in line with the web 37 and aperture 33 in the web 6 and lie beneath the center spring unit of the standard group of springs and the extra spring unit 22 inwardly positioned therefrom and, therefore, serve principally for supporting these spring units. It will be apparent that, although the aforescribed reinforcement is especially designed for the six unit group of springs in accordance with my invention, yet it is admirably adapted for supporting the A. R. A. standard five group nest of springs when the same is positioned so that its longitudinal center line of gravity coincides with the longitudinal center line of the side frame.

From the aforesaid disclosure, it will be seen that I have devised a construction which provides for a twenty per cent increase in spring capacity without radically changing the construction of the side frame, spring plank and associated bolster. With said modified members, the A. R. A. standard five group nest of springs may be employed interchangeably with the spring arrangement disclosed in accordance with my invention although, of course, there will be slightly more clearance between the spring plank embossment 15 and the standard five group nest of springs normally positioned than when employing the spring arrangement disclosed in the present application.

Having now described my invention, what I claim is:

1. In a car truck, in combination, a side frame formed with a bolster opening and a spring plank seat portion beneath said opening, a standard nest of springs supported by said spring plank seat portion of the side frame and an additional spring unit positioned back of the center spring of said group, said standard group being shifted

forwardly so that the whole group balances about the longitudinal center line of the side frame.

2. In a car truck, in combination, a side frame formed with a bolster opening and a spring plank seat portion beneath the bolster opening, a spring plank positioned on said spring plank seat portion of the frame, a standard five unit nest of springs supported 5 on said spring plank above the spring plank seat portion of the frame and an additional spring unit positioned inwardly of the center spring unit of the five unit group, said additional unit being spaced with respect to 10 the other springs corresponding to the spacing between said other springs and the entire group being shifted outwardly so that its center of gravity corresponds with the longitudinal center line of the frame.
- 20 3. In a car truck, in combination, a side frame formed with a compression member, a tension member and bolster column guides spacing intermediate portions of said compression and tension members and leaving a 25 window opening therebetween, the portion of the tension member, beneath the window opening, being laterally widened to form a spring plank seat portion of ample width, a spring plank supported on said seat portion, a standard five unit nest of springs supported 30 on said spring plank, an additional spring unit positioned inwardly on the transverse center line of the central spring of the standard nest of springs, the 35 entire group of springs being shifted outwardly so that its center of gravity coincides with the longitudinal center line of the side frame, a bolster, the corresponding end of which is supported by the springs, and retaining means for said springs serving to 40 place the same under initial tension and acting to properly space the springs with respect to each other, the spring plank and bolster.
- 45 4. In a car truck, in combination, a side frame formed with a bolster opening and a spring plank seat portion underlying said opening, a standard nest of springs supported by means of said spring plank seat portion of the frame and an additional 50 spring unit of the same size as the units of the nest of springs positioned back of the nest of springs on the center line of the group, said combined set of springs being 55 positioned so that its center of gravity substantially coincides with the longitudinal center line of the frame.
5. In a car truck, in combination, a side frame formed with a bolster opening and a 60 spring plank seat portion beneath said opening, a spring plank with its corresponding end supported on said spring plank seat portion and in turn supporting a standard nest of springs, and an additional spring unit positioned back of the center spring of the 65
- nest of springs, the whole group being shifted forwardly so that it balances about the longitudinal center line of the side frame, said spring plank being of standard construction except that it is correspondingly 70 longer to allow for the shifting of the group of springs.
6. In a car truck, in combination, a side frame formed with a bolster opening and a spring plank seat portion beneath the bolster opening, a spring plank positioned on said seat portion of the frame, a standard five unit nest of springs supported on said spring plank above the spring plank seat portion of the frame and an additional spring unit positioned inwardly of the center spring unit of the nest of springs, said additional unit being spaced corresponding with the spacing of the springs of the nest with respect to each other and the entire group 80 being shifted outwardly so that its center of gravity corresponds with the longitudinal center line of the frame, the ends of the spring plank being of standard construction but the plank being correspondingly lengthened intermediate its ends to correspond with the outward shifting of the springs whereby it may be used with a standard nest of springs.
7. In a car truck, in combination, a side 90 frame formed with a compression member, a tension member and bolster guide columns spacing intermediate portions of the compression and tension members and leaving a window opening therebetween, that portion of the tension member, beneath the window opening, being laterally widened to form a spring plank seat portion, a spring plank supported on said seat portion, a standard five unit nest of springs supported 100 on said spring plank, an additional spring unit positioned inwardly on the transverse center line of the central spring of the standard nest of springs, the entire group being shifted outwardly so that its center of gravity coincides with the longitudinal center line of the side frame, a bolster, the corresponding end of which is supported by the springs, spring plates positioned one 105 above and one below said springs and retained by a bolt passing through the plates and through the center spring of the standard nest of springs, the end of the spring plank being apertured to correspond with the bolt, said aperture being elongated 110 toward the longitudinal center line of the frame so that the spring plank may be used with a standard spring arrangement, said spring plank being otherwise of standard construction at its ends but elongated at its intermediate portion to correspond with the outward shifting of the springs.
8. In a car truck, in combination, a side frame formed with a bolster opening and a spring plank seat portion beneath said open- 120
- 125
- 130

- ing, a standard nest of springs supported by said spring plank seat portion of the side frame and an additional spring unit positioned back of the center spring of said group, 5 said group being shifted forwardly so that the whole set of springs balances about the longitudinal center line of the frame, spring plates positioned one above and one below said springs and provided with substantially conical locating bosses on the center line of the frame and adapted for engagement with apertures of standard location, 10 whereby the spring arrangement may be replaced by a standard group of springs in normal position.
- 15 9. In a car truck, in combination, a side frame formed with a bolster opening and a spring plank seat portion beneath the bolster opening, a spring plank positioned on said seat portion of the frame, a standard five unit nest of springs supported on said spring plank above the spring plank seat portion of the frame and an additional spring unit positioned inwardly of the center spring unit of the five unit group, said 20 additional unit being spaced with respect to the other springs corresponding to the spacing between said other springs, spring plates for said springs, said plates being provided with securing means extending 25 therebetween and substantially conical locating bosses arranged to engage standard apertures on the center line of the frame to make the arrangement interchangeable 30 with standard construction.
- 35 10. In a car truck, in combination, a side frame formed with a compression member, a tension member and bolster guide columns spacing intermediate portions of said compression and tension members and leaving 40 a window opening therebetween, that portion of the tension member, beneath the window opening, being widened to form a spring plank seat portion, a spring plank supported on said seat portion, a standard five unit nest of springs supported on said spring plank over the seat portion, an additional spring unit positioned inwardly in line with the central spring of the standard 45 nest of springs, the entire group of springs being positioned outwardly with respect to the normal position of a standard five unit nest so that the center of gravity thereof substantially coincides with the longitudinal 50 center line of the side frame, a bolster, the corresponding end of which is supported by the springs, spring plates positioned respectively above and below said springs and provided with spring positioning flanges 55 and means for holding said spring plates in position with respect to said springs, said spring plates being also provided with substantially conical locating bosses arranged for engaging in normally located apertures 60 in the bolster and spring plank, respectively, 65 whereby the arrangement is interchangeable with the standard arrangement.
- 70 11. In a car truck, in combination, a side frame formed with a compression member, a tension member and bolster guide columns spacing intermediate portions of said compression and tension members and leaving a window opening therebetween, that portion of the tension member, beneath the window opening, being widened to form a spring 75 plank seat portion, a spring plank supported on said seat portion, a standard five unit nest of springs supported on said plank, an additional spring unit positioned inwardly on the transverse center line of the central 80 spring of the nest of springs, the entire group of springs being arranged so that its center of gravity coincides with the longitudinal center line of the side frame, said spring plank being provided with a standard boss at its outer end for cooperating with the outer springs to prevent outward shifting thereof, said boss being positioned farther from the center of the spring plank in accordance with the changed positioning 85 of the standard nest of springs.
- 90 12. In a car truck, in combination, a side frame formed with a compression member, a tension member and bolster column guides spacing intermediate portions of said compression and tension members and leaving a bolster opening therebetween, that portion of the tension member, beneath the bolster opening, being generally box shape in cross section with an upper relatively 95 wide web forming a spring plank seat portion, a lower web narrower than said upper web, upright webs extending between the outer edges of said lower web and the upper web, a spring plank supported on said upper web, a six unit nest of springs supported on said spring plank, said group of springs being arranged so that the center of gravity thereof coincides with the longitudinal center line of the side frame and, for this purpose, comprising three pairs of spring units arranged longitudinally of the frame, the end pairs being positioned outwardly and the intermediate pair being positioned inwardly with respect to the center line of the 100 frame so that the outer spring unit of said pair is arranged substantially central with respect to the springs of the end pairs, the supporting web of the side frame being reinforced for properly supporting said 105 springs by triangular web portions arranged under the outer springs between the upper web and outer upright web, a triangular web between said upper web and inner upright web under the innermost spring, a stool 110 angular in cross section arranged between upper and lower webs of the tension member under the innermost springs of the end pairs of springs, and a plurality of upright 115 transversely extending ribs arranged be- 120 125 130

tween said upper and lower webs under the remaining spring unit of the group, whereby the spring plank seat portion of the side frame is adequately reinforced.

5 13. In a car truck, in combination, a side frame formed with a compression member, a tension member and bolster column guides spacing intermediate portions of said compression and tension members and leaving a 10 bolster opening therebetween, the portion of the tension member, beneath the bolster opening, being formed generally box shape in cross section with an upper relatively wide web serving as a spring plank seat 15 portion and adapted for supporting a spring plank upon which rests a standard five unit nest of springs with an additional spring positioned inwardly on the transverse center line of the central spring unit of said nest 20 of springs, the upper web of said box section being widened to correspond with the six spring units which it supports and, for that purpose, the inner edge thereof reaches a maximum width directly under the extra innermost spring of the group and is reinforced directly beneath said spring by upright webs extending from the inner upright web of the box section, and the outer edge 25 of said upper web is widened to points directly beneath the outermost springs where it extends at uniform width and is reinforced by upright webs extending downwardly from said upper web.

14. In a car truck, in combination, a side 30 frame formed with a compression member, a tension member and bolster column guides spacing intermediate portions of said compression and tension members and leaving a window opening therebetween, that portion 35 of the tension member, beneath the window opening, being widened to form a spring plank seat portion, a spring plank supported on said seat portion, a standard five unit nest 40 of springs supported on said spring plank, and an additional spring unit positioned inwardly in line with the central spring of the standard nest of springs, the entire group 45 of springs being arranged so that its center of gravity coincides with the longitudinal center line of the side frame, a bolster supported by said springs with a substantially horizontal surface formed directly above said 50 springs and corresponding in area with the plan thereof, said horizontal surface being extended locally toward the center of the bolster to allow for the reception of the extra spring unit.

15. In a car truck, in combination, a side 55 frame formed with a bolster opening and a spring supporting portion beneath said opening, a five unit nest of springs supported by said spring supporting portion of the side frame and arranged as two longitudinally spaced pairs of units with the fifth 60 unit positioned centrally thereof, and a

sixth spring unit positioned substantially on the transverse center line of the fifth unit and spaced to correspond with the spacing of the other units, the whole nest of springs being arranged so that the center 70 of gravity thereof lies on the longitudinal center line of the side frame.

16. In a car truck, in combination, a side frame formed with a bolster opening and a 75 spring plank seat portion beneath said opening, a standard nest of springs supported by said spring plank seat portion of the side frame and an additional spring unit positioned transversely of the center of said group, said standard group being 80 shifted transversely so that the whole group balances about the original longitudinal center line of the standard nest of springs.

17. In a car truck, in combination, a side 85 frame formed with a compression member, a tension member and bolster column guides spacing intermediate portions of said compression and tension members and leaving a bolster opening therebetween, that portion 90 of the tension member, beneath the bolster opening, being generally box shape in cross section with an upper relatively wide web forming a spring plank seat portion, a lower web narrower than said upper web, webs extending between the outer edges of said lower web and the upper web, a spring plank supported on said upper web, a six unit nest of springs supported on said 95 spring plank, and comprising three pairs of 100 spring units arranged longitudinally of the frame, the end pairs being positioned outwardly and the intermediate pair being positioned inwardly with respect to the center line of the frame so that the outer spring 105 unit of said pair is arranged intermediate the springs of the end pairs.

18. A side frame for railway car trucks comprising a compression member, a tension member and bolster guide columns 110 spacing intermediate portions of said compression and tension members and leaving a window opening therebetween, that portion of the frame, beneath the window opening, being formed with an upper web relatively wide to serve as a spring plank seat portion, said web being formed with an elongated aperture for receiving the retaining means for the bolster springs when said springs are compressed, said aperture being 115 positioned so that one end overlaps the longitudinal center line of the frame whereby it is adapted for use with a standard spring plank and nest of springs or with a correspondingly altered spring plank and nest 120 of springs having added thereto an additional spring unit positioned transversely of the central spring of said nest of springs.

19. A side frame for railway car trucks comprising a compression member, a tension 125

- member and bolster guide columns spacing intermediate portions of said compression and tension members and leaving a window opening therebetween, that portion of the frame, beneath the window opening, being formed with an upper web relatively wide to serve as a spring plank seat portion, said web being formed with standard spring plank squaring lugs on its upper surface and with an elongated aperture for receiving the retaining means for the bolster springs when said springs are compressed, said aperture being positioned so that its inner end overlaps the longitudinal center line of the frame whereby it is adapted for use with a standard spring plank and nest of springs or with a correspondingly altered spring plank and nest of springs having added thereto an additional spring unit positioned inwardly of the central spring of said nest of springs, the spring plank seat portion of said frame being reinforced for properly supporting either spring arrangement.
20. A spring plate for a six unit spring group formed with a boss adapted to engage
- 25
- within the center spring unit of the five outer spring units of said group, annular spring centering flanges being provided for the other five spring units on said spring plate and spaced substantially conical located bosses arranged on said plate on substantially the longitudinal center line of gravity of the spring arrangement, whereby said bosses are adapted for engagement in corresponding apertures arranged for standard spring plates.
21. A spring plate for a six unit spring group formed with a boss adapted to engage within the most nearly central spring unit of said group, annular spring centering flanges being provided for the other five spring units on said spring plate and spaced located means arranged on said plate on substantially the longitudinal center line of gravity of the spring arrangement, whereby the same are adapted for engagement in corresponding apertures arranged for standard spring plates.

In testimony whereof I affix my signature.
